UNITED STATES PATENT OFFICE.

HENRY PETER CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

1,297,100.

Specification of Letters Patent. Patented Mar. 11, 1919.

Application filed March 18, 1915. Serial No. 15,358.

To all whom it may concern:

Be it known that I, HENRY P. CLAUSEN, a citizen of the United States, residing at Mount Vernon, in the county of West Chester and State of New York, have invented certain new and useful Improvements in Telephone-Exchange Systems, of which the following is a full, clear, concise, and exact description.

10 This invention relates to telephone exchange systems, and more particularly to such systems of the central energy type, the object of this invention being to provide improved signaling means for such systems.

15 In accordance with a feature of this invention means are provided whereby in central energy telephone exchange systems of the two-wire type, when a subscriber has initiated a call, the connection of an exchange connecting circuit with the calling line causes the operation of signaling means at the exchange.

20 In accordance with another feature of this invention there is provided a relay associated with a link circuit and energized over a circuit including a portion of a talking strand of the line during the association of the link with a calling line, and means cooperating with said relay to cause the operation of recall signaling means at the exchange to furnish a signal to the operator upon the hanging up and a subsequent removal of a connected calling subscriber's receiver.

25 30 35 This invention is illustrated in the accompanying drawing in which all apparatus is shown in its normal and unactuated position.

40 There is shown in the drawing a telephone exchange system containing one embodiment of this invention and comprising the usual subscribers' stations A and B, and a cord circuit C located at the central office for interconnecting the subscribers' stations. 45 It is believed that this invention will be fully understood from a description of the operation of the system shown in the drawing, and it will be so described.

50 Supposing subscriber A wishes to converse with subscriber B, A removes his receiver from the switchhook, thereby completing a circuit from battery 5 through the winding of line relay 6, contact 7 of cutoff relay 8, line wires 9 and 10, and contact 11

of cutoff relay to ground. Current in this path actuates line relay 6, completing a circuit for line signal 12.

The operator, observing the line signal 12, inserts the answering plug in the jack indicated by this line signal, thereby closing a circuit from battery 15 through the winding of relay 16, ring contacts of the answering plug and jack and the winding of cutoff relay 8 to ground. Current in this path actuates relay 16 which closes its contact 17, completing a circuit from battery 18 through the winding of relay 19, contact 20 thereof, contact 21 of relay 22, contact 17 of relay 16 and contact 23 of the listening key 24 to ground. There is also completed a path for supervisory signal 31 from battery 30. Relay 19 in operating, opens its contact 20 and closes its contacts 25 and 26. The closure of contact 25 establishes a locking circuit for relay 19, through contact 17 of relay 16 and contact 23 of listening key 24. The closure of contact 26 closes a circuit from battery 30, through supervisory signal 31, contact 26 of relay 19, and contact 27 of relay 28 to ground. It is to be observed that a circuit from battery 32, through the winding of relay 28 and interrupter 33 to ground, intermittently energizes relay 28, thereby causing its contact 27 to be closed intermittently. The circuit which has hereinbefore been traced through the contact 26 of relay 19 and contact 27 of relay 28 is from a point 29 in multiple with the circuit through contact 21 of relay 22 and contact 17 of relay 16 and contact 23 of listening key 24. Therefore the intermittent opening and closing of contact 27 of relay 28, at this time, has no effect on the signal 31. When the answering plug was inserted in the jack indicated by line signal 12 the local circuit established thereby and hereinbefore traced included the winding of cutoff relay 8. The adjustment of this relay however is such that it does not operate until after relay 16 operates. Upon the operation of cutoff relay 8, its contacts 7 and 11 are opened and its contacts 35 and 36 are closed, connecting the line wires 9 and 10 with the ring and tip contacts of the answering jack, respectively. Upon the closure of contacts 35 and 36 of cutoff relay 8 a circuit is established from battery 15, through the winding of

relay 16, ring contacts of the answering plug and jack, line wires 9 and 10, tip contacts of the jack and answering plug and the winding of relay 22 to ground. Current in this path actuates relay 22 which opens its contact 21, interrupting the circuit which is in parallel with contact 26 of relay 19 and contact 27 of relay 28. Thereafter the circuit through the signal 31 is intermittently closed, thereby causing this signal to intermittently flash to give a signal to the operator.

The operator now actuates listening key 24 and connects the operator's telephone set across the limbs of the cord circuit and asks the desired number of the calling subscriber. In operating listening key 24, contact 23 thereof is opened, thereby interrupting the hereinbefore traced locking circuit of relay 19, thereby permitting relay 19 to release, which operation opens at contact 26 the hereinbefore traced flashing circuit for supervisory signal 31. Supervisory signal 31 is thereby effaced. Finding the desired number to be that of subscriber B, the calling plug is inserted in the jack corresponding to B's line, completing a circuit from battery 40 through the winding of relay 41, ring contacts of the calling plug and jack and the winding of cutoff relay 42 to ground. Current in this path actuates relay 41 which opens its contact 43 and closes its contacts 44 and 45. Current in this path also actuates cutoff relay 42 which cuts line relay 46 from line wires 47 and 48, and connects these line wires to the tip and ring contacts of the jack. The closing of contact 45 of relay 41 completes a circuit from battery 50 through supervisory signal 51, contact 52 of relay 76 and contact 45 of relay 41 to ground, operating supervisory signal 51. A circuit is also completed from battery 53, through the winding of relay 54, resistance 55 and contact 45 of relay 41 to ground. Relay 54 however is not operated, for there is a short circuit about the winding of this relay which may be traced from battery 56 through contact 57 of relay 58, contact 59 of relay 54 to the resistance 55. The closure of contact 44 of relay 41 completes a circuit from a source of ringing current 65, through the winding of relay 58, contact 44 of the relay 41, contact 66 of the relay 54, tip contacts of the calling plug and jack, contact 67 of cutoff relay 42, line wires 48 and 47, contact 68 of cutoff relay 42, ring contacts of the jack and calling plug, contact 69 of the relay 54, resistance 70 and battery 71 to ground. Ringing current through the above traced circuit operates ringer 72 at the substation B. Subscriber B, in removing the receiver from the switchhook in response to the operation of ringer 72 completes a path of low resistance for the ringing current. It may

be noted here that relay 58 is marginal and will not operate when in series with the ringer 72 and condenser 73 at substation B, but will operate when the path of low resistance established by the switchhook contact is closed. The removal of the receiver from the switchhook at substation B therefore permits relay 58 to operate, which opens its contact 57, removing the short circuit from about the winding of relay 54 which, in responding, opens its contacts 59, 66 and 69 and closes its contacts 74, thereby closing the normal break in the tip strand of the cord circuit. The opening of contact 66 breaks the circuit through relay 58 which thereupon releases, but the short-circuit for the winding of relay 54 is not again established because contact 59 is open. Upon the closure of contact 74 a circuit is established from battery 40, through winding of relay 41, ring contacts of the calling plug and jack, line wires 47 and 48, tip contacts of the jack and calling plug, contact 74 of relay 54 and the winding of relay 76 to ground. Relay 90 76 operates, effacing supervisory signal 51.

Upon finishing the conversation, subscribers A and B restore their respective receivers to the switchhooks, whereupon relays 22 and 76 release, permitting supervisory signals 31 and 51 to operate to give disconnect signals. If the operator is not busy the answering and calling plugs are removed from the jacks and all apparatus returned to normal position. Suppose, however, that as is frequently the case during busy periods, the operator does not immediately take down the connection, and suppose further that subscriber A desires to immediately make another call. He removes the receiver from the switchhook, thereby causing supervisory signal 31 to intermittently flash, signifying to the operator that subscriber A desires another connection. The manner in which supervisory signal 31 is caused to flash will now be described. When the receiver at substation A is restored to the switchhook, upon the completion of the conversation, the release of relay 22 closes its contact 21, thereby completing for relay 19 the hereinbefore traced circuit, whereupon relay 19 operates, completing the locking circuit for itself which has already been traced. Upon the subsequent removal of the receiver at substation A from its switchhook, relay 22 is operated, thereby permitting supervisory signal 31 to intermittently flash in the same manner as it is caused to flash when the answering plug is inserted in the jack of the calling subscriber. As long then as A's receiver is off the switchhook the supervisory signal 31 will flash intermittently until the operator operates listening key 24.

It is to be noted that by utilizing the pres-

ent invention, the improved signaling system may be applied to telephone exchange systems of the common battery two-wire type merely by the addition of a single 5 relay per cord circuit and interrupter mechanism common to a position or to the exchange.

Quite often, if an operator is busy an answering plug may be inserted in the 10 answering jack of a calling line and then the operator may forget all about the connected calling subscriber, in which case in systems heretofore used, the subscriber obtains very poor service and waits for awhile 15 thinking the operator will answer but after a time finds that he must operate the switchhook a number of times to attract the attention of the operator. By using the present invention, all this annoyance and delay 20 are avoided for the supervisory signal will flash intermittently until the listening key is operated. It will also be seen that the improved means for causing the supervisory signal to give a signal distinct in character 25 for recall purposes overcomes many difficulties heretofore experienced when connected subscriber was trying to attract the attention of the operator to make another call. While plurality of batteries have 30 been referred to in this description, it is to be understood that a single battery may be substituted therefor, and such is the usual practice.

What is claimed is:

35 1. In a telephone exchange system, calling and called subscribers' lines, a link circuit for interconnecting said lines, flashing signaling means associated with the answering end of said link circuit, a central source of 40 current, and two relays coöperating when energized to start and continue the operation of said flashing signaling means to present a signal, one of said relays being energized from said source upon the connection 45 of said link with said calling line over a path including a portion of a talking strand of said link circuit, the other of said relays being energized from said source over a path including a portion of said link and 50 the calling line.

2. In a telephone exchange system, calling and called subscribers' lines, a link circuit for interconnecting said lines, a signaling device associated with the answering end 55 of said link circuit, interrupter mechanism and a source of current at the exchange, a relay energized over a local circuit established upon connection of said link with said calling line and including a portion of a 60 talking strand of said link circuit, a relay actuated upon energization of said first relay to partially associate said signaling device, said interrupter mechanism and said source of current, and a third relay associated with said link circuit and energized 65

over said calling line for completing said association whereby said signaling device is caused to present a signal to the operator.

3. In a telephone exchange system, calling and called subscribers' lines, a link circuit 70 for interconnecting said lines, flashing signaling means associated with the answering end of said link circuit, a central source of current, two relays coöperating when energized to start and continue the operation of 75 said flashing signaling means to furnish a signal, one of said relays being energized from said source upon connection of said link with said calling line over a path including a portion of a talking strand of 80 said link circuit, the other of said relays being energized from said source over a path including a portion of said link and the calling line, and operator controlled means for effacing said signal. 85

4. In a telephone exchange system, calling and called subscribers' lines, a link circuit for interconnecting said lines, recall signaling means associated with the answering end of said link circuit, and two relays 90 adapted to coöperate to cause said recall signaling means to operate to present a signal, one of said relays being actuated during connection of said link with a calling line over a circuit including a portion of 95 a talking strand of said link, and the actuation of said other relay being controlled from the calling substation, said recall signaling means being conditioned for operation by the restoration of the calling subscriber's receiver to the switchhook and 100 operated by a subsequent removal thereof.

5. In a telephone exchange system, calling and called subscribers' lines, a two wire link circuit connecting the lines, a supervisory signaling device, interrupter mechanism, a source of current, a supervisory relay controlled from a connected station and when deenergized connecting the source of current in circuit with the supervisory signaling device to cause continuous operation thereof to furnish a disconnect signal, and a relay operated by the deenergization of the supervisory relay to partially associate the 105 signaling device, the interrupter mechanism 110 and the source of current, the subsequent energization of the supervisory relay causing the completion of said association whereby the supervisory signaling device is caused to operate intermittently to furnish 115 a recall signal.

6. In a telephone exchange system, calling and called subscribers' lines, a link circuit for interconnecting the lines, a signaling device, interrupter mechanism, an operating circuit for the signaling device and the interrupter mechanism, a primary relay energized upon the connection of the link circuit with one of the lines over a path including a portion of a talking strand of the 120 125 130

- link circuit, a supervisory relay in the link circuit and controlled over the connected line, and a secondary relay energized when the primary relay is energized and the supervisory relay is deenergized to close a break in the operating circuit, the subsequent energization of the supervisory relay causing the signaling device to operate intermittently. 20
- 10 7. In a telephone exchange system, calling and called subscribers' lines, a link circuit for interconnecting the lines, a signaling device, interrupter mechanism, an operating circuit for the signaling device and the interrupter mechanism, a primary relay energized upon the connection of the link circuit with one of the lines over a path including a portion of a talking strand of the link circuit, a supervisory relay in the link 25
- 15 circuit and controlled over the connected line, a secondary relay energized when the primary relay is energized and the supervisory relay is deenergized to close a break in the operating circuit, and a short circuit about the interrupter mechanism while the supervisory relay is deenergized, the subsequent energization of the supervisory relay removing the short circuit and permitting the intermittent operation of the signaling device. 30

In witness whereof, I hereunto subscribe my name this 17th day of March, A. D. 1915.

HENRY PETER CLAUSEN.
